UNITED STATES PATENT OFFICE.

GEORGE A. GARLOW, OF CONNEAUT, OHIO.

DOOR HOLDER.

Application filed February 13, 1924. Serial No. 692,539.

To all whom it may concern:

Be it known that I, GEORGE A. GARLOW, a citizen of the United States, and a resident of Conneaut, in the county of Ashtabula, and State of Ohio, have made certain new and useful Improvements in Door Holders, of which the following is a specification:

My present invention relates generally to door holders, and more particularly to 10 holders for swinging doors arranged to support the doors in open position and in such manner that they may be readily released for closed movement when desired, my object being the provision of a simple inexpensive construction capable of effective and 15 efficient use and adaptable to horizontally swinging doors of various sizes and types.

In the accompanying drawings which illustrate my invention and forms a part of 20 this specification:—

Figure 1 is an elevation of the inside of a door frame provided with horizontally swinging doors equipped with my invention;

25 Figures 2 and 3 are vertical transverse sections taken respectively on line 2—2 and 3—3 of Figure 1;

Figure 4 is a detail sectional view through one of the door carried brackets;

30 Figure 5 is a detailed perspective view of the bracket shown in Fig. 4, and,

Figure 6 is a detail perspective view of one of the door holding levers.

Referring now to these figures, I have 35 shown in Figs. 1, 2 and 3, a door frame 10, to the sides of which the outer edges of a pair of horizontally swinging doors 11 are hinged as at 12.

According to my invention each door has 40 secured to its inner face a bracket 13 provided with vertically spaced outstanding ears 14, the ears being apertured as seen at 15, in Fig. 5, for the reception of a pivot pin 16 passing also through a bearing member

45 17 intermediate the ends of a lever 18. This lever is extended between the ears 14, as plainly shown in Figs. 2, 3 and 4, and is of less width than the spaces between the ears 14, and the pivot pin 16 has a loose fit 50 in the bearing member 17 of the lever so that the latter is thus not only swingable on the pivot 16 in a direction parallel to the swinging movement of the door 11, but is also shiftable on pivot 16 vertically or in 55 the direction at right angles to the swinging movement of the door.

At the outer end, each lever has an opening by means of which the upper end of a pull chain 19 may be connected, and at its inner end its lever has at its lower edge a 60 cut out portion or notch 20, and is provided beyond said notch with a cross piece 21, this end of the lever working through the rectangular opening 22 of the depending portion 23 of a bracket 24 secured to the upper 65 portion of the door casing or frame 10 immediately upon the inside of the door.

That portion of each lever inwardly beyond the pivot thereof is as shown, considerably longer than that portion outwardly 70 beyond the pivot and in view of the before mentioned adaptability of the lever to shift vertically, it is obvious that as the door 11 is swung from the closed position of Fig. 1 to the open position of Fig. 2, the lever will 75 be drawn in an outward direction through the apertured frame bracket 24, as in Fig. 3, the lever at the same time swinging horizontally as it yields with and adapts itself to the opening movement of the door. This 80 movement progresses until the notch 20 of the lever reaches the bracket 22, at which point the inner portion of the lever drops downwardly by gravity so that the notch straddles the lower portion of the bracket 85 and thus prevents further movement of the door 11 in either direction, the door being then latched. The inner cross piece 22 arrests the door in the open position shown to prevent the lever from jumping out of place 90 in case the door is opened in any way violently.

When it is desired to close the door it is simply necessary to pull downwardly upon the chain 19 depending from the shorter 95 outer end of the lever so as to rock the lever vertically until the notch 20 is freely above the lower portion of the bracket 24 when it is obvious the door may be again swung inwardly to the closed position.

100 My invention thus proposes a simple economical arrangement for the purposes set forth, as well as one capable of application to a variety of different types of horizontal swinging doors, such as barn doors, garage 105 doors, and the like and my invention further proposes a construction which may be easily and quickly applied and will be effective, efficient and durable in use.

I claim:—

110 1. A swinging door holder including a lever having a notch in its lower edge adja-

cent to one end and a cross piece beyond the notch and having a flexible pull connection at its opposite end, a bracket attachable to a door frame having an aperture through which the first mentioned end of the lever extends, a bracket attachable to a door having vertically spaced horizontally projecting tongues between which the outer portion of the lever extends, said lever having a vertically disposed bearing intermediate its ends, and nearer to its chain carrying end and being of less width than the space between said bracket tongues, and a pivot pin depending through said ears and through said bearing member of said lever, the pin being of less diameter than the bearing member for the purpose described.

2. A holder for swinging doors including

a lever pivotally supported in connection with a door to be controlled upon a pivot intermediate the ends of the lever, and nearer to one end than the other, said lever being swingable parallel to the swinging movement of the door on said pivot and being tiltable on said pivot at right angles to the swinging movement of the door, and having a notch at the end of its longer portion, and a stationary bracket having an opening through which the longer portion of the lever is shiftable and having a portion below the opening for engagement within the notch of the lever when the latter is at the limit of its movement in one direction.

GEORGE A. GARLOW.
